[57] CLAIM

The ornamental design for cribbage game board, as shown and described.

DESCRIPTION

FIG. 1 is a perspective view showing the top and two sides of cribbage game board, showing my new design; FIG. 2 is a top plan view of the embodiment depicted in FIG. 1;

FIG. 3 is a side view of the embodiment shown in FIGS. 1 and 2;

FIG. 4 is another side view, from a different side than in FIG. 3, of the embodiment of FIGS. 1 and 2; and

FIG. 5 is a bottom plan view of the embodiment depicted in FIGS. 1 and 2.
